UNITED STATES PATENT OFFICE.

HENRY M. LINDENTHAL, OF CHICAGO, ILLINOIS.

GARMENT.

1,229,484.

Specification of Letters Patent. Patented June 12, 1917.

Application filed February 12, 1917. Serial No. 148,046.

To all whom it may concern:

Be it known that I, HENRY M. LINDENTHAL, a citizen of the United States, residing at Chicago, in the county of Cook and 5 State of Illinois, have invented certain new and useful Improvements in Garments, of which the following is a specification.

It is an object of my invention to provide new and novel means for adjusting a garment, peculiarly adapted for use in connection with inner or outer garments for men or women, such as coats, jackets, vests, trousers, overcoats or the like, so designed as to be used across the back or front of the garment and when used across the front is adapted to relieve the buttons in front from the strains imposed thereon. A further object is to provide such adjusting means designed to serve the dual purpose of either 20 an adjustment across the back of the garment or a belt across the front.

The above and other features of advantages and capabilities will become apparent from a detailed description of the accompanying drawings in which I have illustrated one form of my invention, but the form there shown is to be understood as illustrative only.

Figure 1 is a perspective view of a vest embodying my invention showing the adjusting straps extending across the front.

Fig. 2 is a rear elevation of the same showing adjusting straps extending across the back instead of the front.

Fig. 3 is a side elevation of the same with the straps extending across the back, and

Fig. 4 is a cross-sectional enlarged view of the buckle showing the adjusting straps connected thereto when in the position shown 40 in Fig. 1.

Referring to the drawings in detail, the vest is of the usual form consisting of the front 10, the back 11, sewed together at the sides at the seams 12. In the seams 12 there 45 is sewed at one end a pair of adjusting straps 13 and 14, one of which straps carries at its free end a buckle 15. The straps are adapted for a dual purpose, that is, both for adjustment and as an ornamental belt and 50 are adapted to be connected together at their free ends by means of the buckle 15 either at the front or back of the garment, as desired. When positioned as shown in Fig. 1, the exposed side of the strap is usually cov-

ered with goods of the same design as the 55 front of the garment, while the opposite side, which is exposed when the straps are in the position as shown in Figs. 2 and 3, is covered with lining material, the same as is used in the back of the garment. Both coverings extend from the extreme ends of the straps into the side seams 12, so that a finished appearance is presented regardless of which position they may be in. When the straps are in the position shown in Fig. 1 60 they not only serve as an ornamental belt, but may also be used for adjusting the vest to the wearer, and, when so used relieve the buttons on the front of the garment from the strains usually imposed thereon, thus 65 preventing the garment in front from "wrinkling or rolling," which would be the result if the buttons were not relieved from the strain or tension. The straps 13 and 14, when connected together across the front of 70 the vest are in alinement with the top of the lower vest pockets 16 and extend through keepers 17, thus tending to hold the top of these pockets in closed position and sufficiently tight so that the surreptitious removal of any object from these pockets 75 would not only be readily detected, but would, in fact, be difficult to remove by any one except the wearer. The keepers 17 also serve the additional function of preventing 80 the straps from upward and downward movement with respect to the garment. When it is desired to use the straps merely for adjusting purposes the free ends are 85 extended across the back of the garment, 90 connected together and adjusted by means of the buckle.

The buckle 15 as shown, is of oblong form made in one piece in the center of which is a bar 18 to which one end of the 95 strap 14 is secured, as best shown in Fig. 4. On either side of the bar 18 the buckle 15 is, on its under vertical sides, provided with flanges 19, which, when the strap 13 is drawn therethrough, tend to bite into it and 100 securely hold it in place.

While I have herein described my invention as applied to a vest, I do not wish to be understood as limiting its use to that particular garment, as it is adapted for use in 105 connection with any garment for men or women where adjustment is desired.

Various changes and modifications may be

made by those skilled in the art without departing from the scope of my invention as defined in the appended claim.

Having thus described my invention I claim:

In a vest comprising a front and back and provided with the usual lower side pockets and connecting side seams, a pair of straps secured at one end to said side seams and 10 adapted to be readily connected together at their opposite ends either across the front or back of the vest, one surface of said straps being of the same goods as the back

of the vest and the opposite surface being of the same goods as the front of the vest, 15 said straps being adapted when connected together across the front of the vest to tend to hold the lower front pockets in closed position.

In witness whereof, I hereunto subscribe 20 my name to this specification in the presence of two witnesses.

HENRY M. LINDENTHAL.
